(57) **CLAIM**

The ornamental design for a fishing lure, as shown and described.

DESCRIPTION

FIG. 1 is a perspective view of a fishing lure showing my new design;

FIG. 2 is another perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof;

FIG. 8 is a left view thereof;

FIG. 9 is a cross sectional view thereof;

FIG. 10 is a perspective view of a second embodiment of the design;

FIG. 11 is another perspective view of a second embodiment of the design;

FIG. 12 is a front view of a second embodiment of the design;

FIG. 13 is a rear view of a second embodiment of the design;

FIG. 14 is a top view of a second embodiment of the design;

FIG. 15 is a bottom view of a second embodiment of the design;

FIG. 16 is a right view of a second embodiment of the design;

FIG. 17 is a left view of a second embodiment of the design; and,

FIG. 18 is a cross sectional view of a second embodiment of the design.

The portions illustrated in solid lines form part of the claimed design. The portions illustrated in broken lines form no part of the claimed design. Dot dash line is a boundary of the claimed part and the non-claimed part.

1 Claim, 8 Drawing Sheets
